(57) **CLAIM**

The ornamental design for a fluid container spout with straw, as shown and described.

DESCRIPTION

FIG. 1 is a front, top, and side perspective view of a fluid container spout with straw embodying our new design. FIG. 2 is a front view thereof.

FIG. 3 is a back side view thereof.

FIG. 4 is a left side view thereof.

FIG. 5 is a right side view thereof.

FIG. 6 is a top view thereof; and,

FIG. 7 is a bottom view thereof.

Broken lines are used to illustrate features of the fluid container spout with straw which form no part of the claimed design. Broken lines showing the lid, strap, top inner floor, hole in the top inner floor, top inner sidewall, a portion of the external surface of the straw, the internal surface of the straw, and features on the bottom of the spout form no part of the claimed design.
